TABLE LEG FASTENING MEANS

Abraham J. Shoenberg, Clinton, Mass., assignor
to Empire Furniture Manufacturing Company,
Clinton, Mass., a corporation of Massachusetts

Application January 18, 1946, Serial No. 641,937

8 Claims. (Cl. 311—113)

1

This invention relates to tables, and more particularly to an improved construction for fastening the upper portions of the table legs to the frame.

In manufacturing tables with wooden legs, it has long been the practice to provide a frame comprising four separate boards, known as "aprons," which are positioned in a generally rectangular arrangement, with their wide surfaces in vertical planes. The ends of the aprons terminate somewhat short of the corners of the rectangle, and the end portions of the aprons are connected by cleats or braces located within the frame. The upper portions of the wooden legs are square and fit against the ends of the aprons, being held in place by screws extending through the cleats and into the legs. While this is satisfactory with wooden legs, it has heretofore been considered necessary to employ a modified frame construction for use with metal legs, and particularly with legs of the double tubular type. Furthermore, the constructions heretofore proposed for attaching metal legs have been expensive, unsightly, and lacking in the required strength and rigidity.

It is accordingly one object of the invention to provide a simple and comparatively inexpensive construction for attaching metal legs to a table frame, and particularly to frames of the type commonly used with wooden legs.

It is a further object of the invention to provide a table having a wooden frame and metal legs rigidly and firmly attached thereto by means presenting an attractive appearance.

It is a further object of the invention to provide a comparatively simple and highly effective bracket for attaching metal legs of the double tubular type to the corners of a table frame.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is a plan view of a table, with a portion of the table top broken away at one corner;

Fig. 2 is a front elevation of the table;

2

Fig. 3 is an enlarged view of a portion of Fig. 1; and

Fig. 4 is a perspective view of a bracket.

The embodiment illustrated comprises a frame including four horizontally extending wooden boards or aprons 10 (of which only two appear in the drawings). These aprons are positioned in a generally rectangular arrangement, their wide surfaces being located in vertical planes, and their adjacent ends being somewhat spaced apart. At each corner of the frame the adjacent portions of the aprons are connected by a cleat or brace 11, which extends across the inside of the corner at an angle of forty-five degrees with the aprons. As shown, the aprons are notched to receive the ends of the cleat, which are fastened to the aprons by means of screws 12. The aprons 10 support the usual flat table top 14.

In order that the frame 10—11 may be used with tubular metal legs instead of the usual wooden legs, a novel bracket 18 is provided. This bracket is preferably formed of sheet metal, and as best shown in Fig. 4 it comprises a vertical flat central plate 19 and two curved portions 20 located at opposite sides of the central plate. The portions 20 are shaped to provide vertical cylindrical channels which are integrally joined to the central plate 19 by flat connecting portions 22 substantially tangential to the portions 20 and meeting the front or outer surface of the plate 19 at obtuse angles. The front surfaces of the curved portions 20 are convex. It is not necessary that the portions 20 form complete cylinders, but they preferably extend for more than half of a circle. In the embodiment illustrated they extend for approximately 225 degrees, and their axes lie in substantially the same plane as the central plate 19. The plate 19 is provided near its center with a square hole 23, and each portion 20 is provided near its upper edge with a small indentation 24 which forms a small bulge or protuberance 25 (Fig. 3) on the inside of the channel.

Referring now to the assembled table construction as shown in Figs. 1 to 3, it will be apparent that one of the brackets 18 is provided at each corner of the table frame, and that each curved portion or channel 20 receives the upper portion of a vertical tubular metal leg element 27 which fits the channel closely. The upper

ends of the leg elements engage the protuberances 25, which serve as stop lugs. The two leg elements 27 at each corner may be entirely separate from one another or, as illustrated, they may be integrally joined at their lower ends by a U-shaped portion 28 adapted to engage the floor. Each bracket 18 is connected to the adjacent cleat 11 by means of a carriage bolt 30 having an outer head 31 and a square portion 32 which extends through the opening 23 in the central plate 19. This plate extends across the corner of the table frame, and the curved portions 20 extend in front of the leg elements and overlap the adjacent end portions of the aprons 10. Thus the ends of the aprons are entirely concealed in the completed table, providing a neat and attractive structure. By tightening the bolt 30, a clamping pressure will be applied to the front surfaces of the leg elements by the curved portions 20, and the bracket and leg elements will be drawn firmly against the aprons. Thus the leg elements are clamped between the bracket and the adjacent portions of the aprons. The construction obviously permits vertical adjustment of the leg elements relative to the aprons, if necessary, in order that the table may set properly upon an uneven floor.

Since the frame construction is the same as is customarily used with wooden legs, it will be apparent that a manufacturer may produce a stock of frames and then attach either wooden legs or tubular metal legs as the requirements of his customers may dictate. This will appreciably reduce the cost of manufacture and the amount of inventory necessary. The bracket 18 may be formed by a simple bending operation from inexpensive sheet steel, and it is preferably plated with chromium or the like as a protection against rust and to enhance its appearance.

Having thus described my invention, what I claim as new and desire to secure by Letters Patent is:

1. A table comprising two horizontally extending aprons positioned at an angle to one another with their adjacent ends terminating somewhat short of the apex of the angle, a cleat located inside the angle to connect the adjacent end portions of the aprons, a metal bracket extending across the ends of the aprons, the bracket including a central portion and two vertical channels on opposite sides of the central portion, fastening means connecting the central portion of the bracket to the cleat, and two upright tubular metal leg elements with their upper portions located in the respective channels.

2. A table comprising two horizontally extending aprons positioned at an angle to one another with their adjacent ends terminating somewhat short of the apex of the angle, a cleat located inside the angle to connect the adjacent end portions of the aprons, a bracket including an upright central plate extending across the ends of the aprons and two curved portions at opposite sides of the plate overlapping the end portions of the aprons, the curved portions forming upright channels, fastening means connecting the central plate to the cleat, and two upright leg elements with their upper portions located in the respective channels.

3. A table comprising two horizontally extending aprons positioned at an angle to one another with their adjacent ends terminating somewhat short of the apex of the angle, a cleat located inside the angle to connect the adjacent end portions of the aprons, a bracket including an upright cen-

cluding an upright central plate and two curved tral plate extending across the ends of the aprons and two curved portions at opposite sides of the plate overlapping the end portions of the aprons, the curved portions forming upright channels, fastening means connecting the central plate to the cleat, two upright leg elements with their upper portions located in the respective channels, and a stop lug on the inner surface of each channel near the top thereof to engage the upper end of the corresponding leg element.

4. A table comprising two horizontally extending aprons positioned at an angle to one another with their adjacent ends terminating somewhat short of the apex of the angle, a cleat located inside the angle to connect the adjacent end portions of the aprons, two upright leg elements with their upper portions engaging the outer surfaces of the respective aprons near the ends thereof, a bracket extending across the upper portions of both leg elements and in front thereof to clamp them against the aprons, and fastening means connecting the central portion of the bracket to the cleat.

5. A table comprising two horizontally extending aprons positioned at an angle to one another with their adjacent ends terminating somewhat short of the apex of the angle, a cleat located inside the angle to connect the adjacent end portions of the aprons, a bracket extending across the ends of the aprons, the bracket including a central portion and two upright channels on opposite sides of the central portion, fastening means connecting the central portion of the bracket to the cleat, and two upright leg elements with their upper portions located in the respective channels.

6. A table comprising two horizontally extending aprons positioned at an angle to one another with their adjacent ends terminating somewhat short of the apex of the angle, a cleat located inside the angle to connect the adjacent end portions of the aprons, two upright leg elements with their upper portions located adjacent the end portions of the aprons, a bracket extending across in front of the leg elements, the bracket including a central portion and two upright channels on opposite sides of the central portion, the upper portions of the leg elements being positioned within the respective channels, and fastening means connecting the central portion of the bracket to the cleat.

7. A table comprising two horizontally extending aprons positioned at an angle to one another with their adjacent ends terminating somewhat short of the apex of the angle, a cleat located inside the angle to connect the adjacent end portions of the aprons, two upright leg elements with their upper portions adjacent the end portions of the aprons and in front thereof, a bracket extending across the upper portions of the leg elements and in front thereof, and fastening means connecting the central portion of the bracket to the cleat and arranged to pull the bracket rearwardly toward the cleat, thereby clamping the leg elements between the bracket and the adjacent portions of the aprons.

8. A table comprising two horizontally extending aprons positioned at an angle to one another with their adjacent ends terminating somewhat short of the apex of the angle, a cleat located inside the angle to connect the adjacent end portions of the aprons, two upright leg elements with their upper portions adjacent the end portions of

the aprons and in front thereof, a bracket in-
portions at opposite sides of the central plate
forming upright channels, the curved portions ex-
tending across the upper portions of the respec-
tive leg elements and in front thereof, and fas-
tening means connecting the central plate to the
cleat and arranged to pull the bracket rearwardly
toward the cleat, thereby clamping the leg ele-
ments between the curved portions of the bracket
and the adjacent portions of the aprons.

Certificate of Correction

Patent No. 2,485,784

October 25, 1949

ABRAHAM J. SHOENBERG

It is hereby certified that errors appear in the printed specification of the above numbered patent requiring correction as follows:

Column 4, line 1, strike out the syllable and words "cluding an upright central plate and two curved" and insert the same in column 5, line 1, after the syllable and hyphen "in-";

and that the said Letters Patent should be read with these corrections therein that the same may conform to the record of the case in the Patent Office.

Signed and sealed this 14th day of February, A. D. 1950.
